UNITED STATES PATENT OFFICE.

JOHN M. WOOTAN AND LAWRENCE M. WOOTAN, OF SMITHS TURN OUT, SOUTH CAROLINA.

WRENCH.

1,070,571.

Specification of Letters Patent.

Patented Aug. 19, 1913.

Application filed May 18, 1912. Serial No. 698,302.

To all whom it may concern:

Be it known that we, JOHN M. WOOTAN and LAWRENCE M. WOOTAN, citizens of the United States, residing at Smiths Turn Out, 5 in the county of York and State of South Carolina, have invented new and useful Improvements in Wrenches, of which the following is a specification.

The general object of this invention is the provision of a combination tool having an adjustable jaw of novel construction which is adapted, in connection with a sliding jaw, to be used as a combined nut and pipe wrench, said sliding jaw being operated by a 15 novel means mounted in the handle of said tool.

In carrying out the objects of the invention generally stated above, it will be understood, of course, that the essential features 20 thereof are susceptible to changes in details and structural arrangements, one preferred and practical embodiment being shown in the accompanying drawing, wherein:

Figure 1 is a side elevation of the tool constructed in accordance with the invention. Fig. 2 is an end elevation thereof. Fig. 3 is a vertical longitudinal sectional view thereof. Fig. 4 is a section on the line 4—4 of Fig. 1. Fig. 5 is a section on the line 5—5 30 of Fig. 1.

Referring more particularly to the accompanying drawing in which like reference characters designate similar parts, it will be seen that the invention comprises a handle 10 having an elongated opening 11 extending longitudinally thereof for the greater portion of its length. The inner end of the handle 10 is provided with a transverse stationary jaw 12. Slidably mounted in the reduced passage 13 of the opening 11 is the shank 14 of the movable jaw 15 extending in parallel relation to the stationary jaw 12. The jaw 15 is curved at one end as indicated at 16 to provide a nail extractor and is also 45 serrated as indicated at 17 to provide a gripping surface for the said jaw when the tool is used as a pipe wrench.

The inner end of the shank 14 is provided with a notch and lug 18 and 19 respectively 50 which are adapted to interlock with a similar notch and lug 20 and 21 formed upon the adjacent end of a rack bar 22 having the teeth 23 on one longitudinal edge thereof. The rack bar 22 is adapted to slide in an 55 opening 24 formed in the locking pawl 25,

said pawl being provided at one end with a curved extension 26 which is adapted to engage a curved opening 27 which is formed in one of the walls of the main opening 11. The locking pawl 25 is adapted to normally 60 extend transversely of the opening 11 at an angle to the longitudinal axis of the handle 10 whereby one of the edges of the opening 24 will engage the teeth 23 of the rack bar 22 and thus prevent outward movement of 65 the jaw 15. Said pawl 25 is retained in the position just described by means of a spring pressed block 28 which bears against the adjacent free end of the pawl 25 and which is provided with a stem 29 which is mounted 70 in an opening 30 formed in the shoulder 31, the spring 32 being adapted to engage the block 28 in order to retain the same in a normally extended position. In order to release the pawl 25 from locking engagement with 75 the rack bar 22, a sliding arm 33 is mounted in the opening 11 between the said rack bar and adjacent wall of said opening, the inner end of said arm being adapted to engage the free end of the pawl 25. The other 80 end of the sliding arm 33 is provided with a finger knob 34 which projects through an elongated opening 35 formed in the handle 10. It will thus be seen that pressure upon the knob 34 toward the free end of the handle 10 will cause the sliding arm 33 to force the locking pawl into a position substantially at right angles to the longitudinal axis of said handle and thereby release the pawl 85 from locking engagement with the rack bar. 90 This movement will also cause the rack bar to draw the movable jaw 15 inwardly in order to adjust the same and when pressure is released upon the knob 34 the spring pressed block will cause the said pawl to return to its normal position. It will thus be 95 obvious that a continued reciprocating movement imparted to the sliding arm 33 will effect a step by step adjustment of the movable jaw 15.

When it is desired to use the tool as a pipe wrench, an adjustable jaw 36 is mounted upon the shank 14 of the movable jaw 15 and secured thereto by means of a set screw 37. The jaw 36 is provided with an 105 inclined portion as indicated at 38 upon the outer surface thereof, said inclined surface being provided intermediate the ends thereof with the stop shoulders 39 for a purpose presently described. Extending longitudi- 110

nally of the inclined surface 38 for a portion of its length is a raised seat 40 having its longitudinal edges beveled inwardly as indicated at 41, said seat being adapted to receive a sliding wedge block 42 having a longitudinal channel 43 therein, the walls 44 of said channel being beveled and adapted to engage the beveled edges of the seat 40 thus forming an interlocking dove-tail joint therebetween. The wedge block 42 is cut away at its inner end to provide extensions 45 from which depend the stops 46 which are adapted to engage the stop shoulders 39 in order to limit the outward movement of the said block. Carried by the block 42 is a longitudinally extending auxiliary jaw 47 which has its bearing surface serrated as indicated at 48, said jaw being provided at its outer extremity with a laterally projecting extension 49 which is adapted to engage the longitudinal opening 50 formed in the seat 40 when the wedge block 42 is forced inwardly by reason of the turning movement imparted to the tool in one direction when the serrations 17 of the jaw 15 and the auxiliary jaw 47 are in engagement with the pipe. It will thus be seen that the turning of the tool will cause the wedge block 42 to slide inwardly upon the jaw 36 and thereby cause the auxiliary jaw 47 to obtain a firmer grip upon the pipe. A coil spring 51 is mounted in the opening 50 formed in the seat 40 and the outer end of said spring engages the inner surface of the extension 49 whereby upon the release of the jaw 47 from a pipe, said spring will force the wedge block 42 to its normal position.

What is claimed is:—

40 1. A tool comprising a handle having a longitudinally extending opening therein, a fixed jaw carried by said handle, a movable

jaw having a shank slidably mounted in said handle, a rack bar mounted in said opening and adapted for interlocking engagement with the inner end of said shank, a locking pawl in said handle mounted for swinging vertical movement with respect to the rack bar, and having an opening for the reception of said rack bar, and spring 45 pressed means mounted in said handle and engaging the free end of said pawl for retaining the same in locking engagement with said rack bar, and an arm slidably mounted in the handle and engaging the pawl in 50 opposition to the spring pressed means whereby in the movement of the arm the pawl will impart a longitudinal movement to the rack bar.

2. A tool comprising a handle having a 60 longitudinally extending opening therein, a fixed jaw carried by said handle, a movable jaw having a shank slidably mounted in said handle, a rack bar mounted in said opening and adapted for interlocking engagement 65 with the inner end of said shank, a locking pawl pivoted in said handle and having an opening for the reception of said rack bar, spring pressed means mounted in said handle and engaging the free end of said pawl 70 for retaining the same in locking engagement with said rack bar, and means slidably in said opening and engaging the free end of said pawl for releasing the same from locking engagement with said rack bar and 75 imparting a longitudinal movement to the rack bar.

In testimony whereof we affix our signatures in presence of two witnesses.

JOHN M. WOOTAN.

LAWRENCE M. WOOTAN.
